UNITED STATES PATENT OFFICE.

FREDERICK B. CUSHMAN, OF NORTH BENNINGTON, VERMONT, ASSIGNOR TO H. T. CUSHMAN MFG. CO., OF NORTH BENNINGTON, VERMONT, A CORPORATION OF VERMONT.

DESIGN FOR A COMBINED SMOKER'S STAND AND MAGAZINE RACK.

Application filed March 14, 1927. Serial No. 21,130. Term of patent 3½ years.

To all whom it may concern:

Be it known that I, FREDERICK B. CUSHMAN, a citizen of the United States, residing at North Bennington, in the county of Bennington and State of Vermont, have invented a new, original, and ornamental Design for a Combined Smoker's Stand and Magazine Rack, of which the following is a specification, reference being had to the accompanying drawings, forming part thereof.

Drawings.

The single figure is a perspective view of a combined smoker's stand and magazine rack showing my new design.

I claim:

The ornamental design for a combined smoker's stand and magazine rack substantially as shown.

FREDERICK B. CUSHMAN.
